(57) **CLAIM**

We claim the ornamental design for a flow cell cartridge, as shown and described.

DESCRIPTION

FIG. 1 is a top, rear perspective view of a flow cell cartridge comprising our new design;

FIG. 2 is a top plan view of the design in FIG. 1;

FIG. 3 is a bottom plan of the design of FIG. 1;

FIG. 4 is a left side elevational view of the design of FIG. 1;

FIG. 5 is a right side elevational view of the design of FIG. 1;

FIG. 6 is a front elevational view of the design of FIG. 1; and,

FIG. 7 is an enlarged rear elevational view of the design of FIG. 1.

The evenly broken lines shown in the drawings illustrate portions of the flow cell cartridge that form no part of the claimed design. The dot dash broken lines depict the boundaries of the claim and form no part thereof.
